UNITED STATES PATENT OFFICE.

SEBASTIANO MAGNANO, OF LAWRENCE, MASSACHUSETTS, ASSIGNOR TO MAGNANO CORPORATION, OF LAWRENCE, MASSACHUSETTS, A CORPORATION OF MASSACHUSETTS.

STOP MECHANISM.

Application filed April 10, 1924. Serial No. 705,647.

This invention pertains to machines for feeding articles one by one in succession from a stack or magazine and relates more particularly to automatic mechanism for stopping the machine whenever during its orderly operation it fails to deliver an article from the stack or magazine at the proper time.

In order more clearly to set forth the new and advantageous functions arising from the use of this invention it is herein illustrated by way of specific example as embodied in a multiple magazine machine for placing metallic drop wires upon loom warp threads and as applied to this particular mechanism its principal object is to provide means for stopping the entire machine whenever a drop wire fails to feed at the proper time from any of the magazines.

20 In the accompanying drawings which illustrate a preferred embodiment of the invention:

Fig. 1 is a fragmentary side elevation of the forward or delivery end of a machine for placing drop wires upon loom warp threads;

Fig. 2 is a similar fragmentary side elevation from the opposite side of the machine from that shown in Fig. 1;

Fig. 3 is a front elevation of the machine, certain parts being omitted and certain parts being shown in section;

Fig. 4 is a fragmentary vertical section substantially on the line 4-4 of Fig. 3 showing the parts as positioned during the orderly operation of the machine and showing the drop wires as feeding successively toward the plane of the warp threads;

Fig. 5 is a view similar to Fig. 4 but indicating one of the magazines as being empty and showing the last drop wire from said magazine as just engaging a selected warp thread;

Fig. 6 is a view similar to Fig. 5 but showing the parts at a later stage in the operation where the failure of further drop wires to feed has resulted in operation of the stop mechanism; and

Fig. 7 is a diagrammatic view showing a desirable form of electrical circuit and connections in accordance with the present invention.

Referring to the drawings for a more detailed description of the mechanism, the numerals 1 and 2 respectively indicate opposite side members of the supporting

frame of the machine. These side members are held in properly spaced relation by means of transverse bars or shafts, two of which are indicated at 3 and 4 respectively, Fig. 4. The frame is supported for bodily movement upon wheels or rollers 5 and 6 which rest upon rails 7 adapted to be disposed transversely across a sheet of warp threads to which the drop wires are to be applied.

A main drive shaft 8 is journaled in the upper part of the frame at its forward end and this shaft is furnished at opposite ends with cranks 9 which transmit the motion of the drive shaft by means of suitable slide bars or connecting rods 10 to the warp selecting and positioning mechanism indicated generally at 11. As this mechanism forms no part of the present invention, its further description is unnecessary.

The shaft 8 is also provided with a gear forming one of a train of gears indicated generally at 12, one of said gears being mounted upon a shaft carrying a crank 13 which actuates a connecting rod 14, the latter operating suitable mechanism, not shown, for feeding the drop wires toward the delivery end of the machine.

The drop wires are contained in a magazine or magazines in which they are arranged in compact series. In the machine herein disclosed four substantially like and parallel magazines are employed. Each machine comprises a supporting bar 15 over which the drop wires of hairpin type are straddled. These bars are of such thickness and depth that they support the drop wires in proper position without requiring any side walls or other elements to keep the drop wires in proper position during their forward travel toward the delivery end of the machine.

The forward ends of the several magazines are defined by a transverse plate 16 secured to the frame members 1 and 2 and which is spaced from the forward ends of the magazine bars 15 a distance 17 substantially equal to the thickness of one of the drop wires. This plate 16 is furnished with a vertical slot 18 substantially in the plane of each of the magazine bars 15. A picker pin 19 projects through each of the slots 18 to a distance substantially equal to or slightly less than the thickness of a drop wire. These picker pins are carried by heads

21 sliding upon vertical bars 20 secured to the forward or outer face of the plate 16. The several heads 21 are connected by suitable connecting rods 21^a to cranks carried by a shaft 22 which receives its motion from one of the train of gears 12.

The cranks upon the shaft 22 are disposed substantially 90° apart so that the several heads 21 with their picker pins 19 are moved successively up and down. In the arrangement shown the result is that a drop wire from one or another of the magazines is always in process of delivery, such wires being engaged by the descending picker pins and forced downwardly through the space 17 toward the plane of the warp threads.

As each drop wire is ejected from the magazine its lower end is caught between a pair of feed rollers 23 and 24. The roller 23 is mounted upon the shaft 25 which is provided with a gear meshing with one of the gears of train 12 so that the roller 23 is positively driven and constitutes a feed roll for progressing the drop wire after its delivery from the magazine toward the warp threads. The cooperating feed roll 24, which may be termed a detector roll, is mounted in bearings carried by a swinging frame or lever 26 carried by a shaft supported by the frame. A spring 27 engages the lever device 26 and normally tends to force the roll 24 into engagement with the roll 23.

As the drop wires are fed downward by the rolls 23 and 24 their lower ends come in contact with a fixed spreader device 28. At substantially the same time an oscillating bar 29 engages the drop wire and forces it rearwardly against the spreader 28 so that its legs L and L' are sprung apart to permit them to pass upon opposite sides of the warp thread W which has been selected and positioned by the mechanism 11.

In the preferred arrangement the drive shaft 8 is actuated by an electric motor 30, Fig. 7. One terminal of this motor is connected to a conductor 41 leading from a suitable source of power. The other terminal of the motor is connected to a wire 35 connected to an insulated contact pin 36 (Fig. 6), carried by a bracket 37 mounted on the frame member 2. A movable contact pin 38 is arranged to cooperate with the pin 36. This movable contact pin 38 is carried by one arm 39 of a bell crank lever. Pin 38 is insulated from the arm 39 and is connected by a conductor 41 to the source of power through which the motor receives its energy. The other arm 31 of the bell crank lever is connected to an arm 32 projecting from the lever device 26 which carries the detector roll 24. The arms 31 and 32 are preferably united by a pin and slot connection or equivalent device.

While the circuit as above described is sufficient for the purposes of the present in-

vention it is preferred to combine therewith suitable connections operative for stopping the machine upon breakage of the warp thread to which the drop wire is being applied. For this purpose a circuit breaker is 70 interposed in the conductor 41. This circuit breaker comprises terminals 42 and 43 which normally contact, one of said terminals being carried by a movable member 45 constituting or carrying the armature of an 75 electro-magnet 46. One terminal of the magnet is connected by a conductor 47 to a battery or other source of power indicated at 48, the other terminal of the battery being grounded upon the frame of the machine 80 through a wire 49.

50 indicates a fixed contact element insulated from the frame of the machine and connected by a conductor 51 to the opposite terminal of the electro-magnet 46. A movable contact element 53 is associated with the warp-separating and positioning mechanism 11. This contact 53 is carried by a vertically sliding frame having a warp engaging member 54 at its lower end. This warp engaging member 54 constitutes a feeler and so long as it is supported by the warp threads it holds the contact member 53 up out of engagement with the contact 50. If through slackening, breakage or other cause the warp threads fail to hold the member 54 in normal position, it drops, permitting contact 53 to engage contact 50. As contact 53 is grounded on the frame of the machine the circuit is completed through the electro-magnet 46 100 and the motor circuit is broken between the contacts 42 and 43.

If desired a switch 41^a may be disposed in the conductor 41 for the manual control of the motor.

Referring particularly to Fig. 4 the mechanism is indicated as in operative position, the contacts 36 and 38 being engaged so that the motor circuit is complete. One of the drop wires D is shown as having been fed down by the picker and as being gripped between the rolls 23 and 24 which are feeding it still further downwardly toward the warp threads. A second drop wire D' has just been engaged by the corresponding picker and is moving downwardly from the magazine but has not as yet been engaged by the rolls 23 and 24. Due to the successive action of the several picker fingers a continuous stream of drop wires is fed down between the rolls 23 and 24 which extend transversely substantially across the entire width of the machine, and so long as a single drop wire is held between the rolls the spring 27 is unable to move them into contact.

In Fig. 5 the parts are shown as they would appear had the last drop wire been fed from one of the magazines. In this figure the drop wire D^a represents a wire which has been brought from a magazine not yet 130

depleted while the picker pin 19^a of the empty magazine has nearly reached the bottom of its stroke but without ejecting a drop wire from the magazine. At this time two 5 of the pickers are on their way up and the fourth is just beginning its down stroke so that as the drop wire D² passes from between the rolls 23 and 24 no other wire is ready to be gripped between said rolls. Accordingly 10 as the wire D² emerges from the rolls the detector roll swings over into contact with the roll 23 as shown in Fig. 6. As the arm 32 moves with the roll 24 the arm 39 of the bell crank lever is immediately swung to carry the contact 38 away from the contact 36 thus breaking the circuit at this point and stopping the motor.

The machine is thus stopped automatically whenever for any reason the drop wires fail 20 to feed in orderly succession from the several magazines onto successive warps of the series. As the machine stops upon any failure of a drop wire to feed, the operator is thus enabled to note the absence of a drop wire 25 from its corresponding warp so that there is no danger that warps will be missed during the operation of placing wires thereon.

When the machine has stopped and the magazine has been replenished or any other 30 cause of failure has been noted and corrected, the machine may be started manually and operated until a wire has passed down between the rolls 23 and 24 whereupon the circuit is completed and the orderly operation of the machine continues.

While the above mechanism is particularly well adapted for use in machines for feeding drop wires in its broader aspects it is of utility in other situations whenever articles 40 are to be fed in succession from a magazine.

I claim:

1. In a machine of the class described feed means for propelling elongate thin sheet material elements, said feed means comprising a pair of cooperating feed members to one at least of which a feed motion is normally imparted, said members being disposed simultaneously to engage opposite surfaces of one 50 of said elongate elements one of said parts being movable bodily toward and from the other, means resiliently urging said members relatively toward each other to produce a gripping feed pressure, said members being separated in the normal operation of the machine solely by the elongate element which is gripped between them, and means responsive to abnormal approach of said parts in the absence of such element from between them to stop the normal feed movement of said parts.

2. In a machine of the class described, means for propelling detached loom elements, said means comprising a pair of feed rolls, one at least of said rolls being bodily 55

movable toward and from the other, means tending to urge said movable roll toward the other roll to produce a gripping feed pressure between them, and means responsive to abnormal approach of the rolls in the absence of such a detached loom element from between them to stop the rotation of the driven roll.

3. In a machine for applying drop wires to loom warps, a drive shaft, a magazine for holding a series of drop wires, a drive element, a reciprocatory picker for ejecting drop wires one by one from the magazine, a pair of rolls between which the ejected drop wires are gripped, one of said rolls being bodily movable toward and from the other, a spring tending to move the bodily movable roll into engagement with the other roll, and means operative in response to abnormal approach of the rolls in the absence of a drop wire between them to stop the drive element.

4. In a machine for applying drop wires to loom warps, a drive shaft, a magazine for holding a series of drop wires, a picker for ejecting said wires one by one from the magazine, a feed roll, a second feed roll mounted to move bodily toward and from the front roll, a power shaft, connections for transmitting movement from the shaft to the picker and feed roll, a spring tending to urge the bodily movable roll into contact with the feed roll whereby resiliently to grip and feed forward each drop wire as it is ejected from the magazine, and means operative in response to abnormal approach of said rolls in the absence of a drop wire from between them to stop the power shaft.

5. In a machine of the class described, a magazine for independent thin sheet metal elements, means for ejecting them one by one from the magazine, a feed roll, a second roll bodily oscillable toward and from the feed roll, said rolls gripping and feeding forward the successive elements as delivered from the magazine, a spring urging the bodily movable roll toward the feed roll to exert feeding pressure upon the elements interposed between the rolls, means for driving the operative parts of the machine, a stop device, and a link connecting the stop device with the bodily movable roll whereby, upon abnormal approach of the latter roll toward the feed roll in the absence of one of the sheet metal elements from between them, the stop device will be actuated by means of said spring to stop the machine.

6. In a machine for applying drop wires to loom warps, a magazine, means for ejecting drop wires one by one from the magazine, a feed roll, a detector roll movable bodily toward and from the feed roll, a spring urging the detector roll toward the feed roll for resiliently gripping the drop wires between the rolls as they are ejected from the magazine, an electric motor for 125 130

driving the machine, a circuit breaker for determining the supply of current to the motor, and means operative in response to abnormal approach of the detector roll toward the feed roll to actuate the circuit breaker to cut off current from the motor.

7. In a machine of the class described a pair of feed rolls between which independent thin sheet metal elements are gripped and fed during the normal operation of the machine, one of said rolls being mounted upon a pivoted support to move bodily toward and from the other, a spring urging said bodily movable roll toward the other to produce feeding pressure between the rolls, an electric motor for driving the machine, separable, normally engaging contacts in the circuit of said motor, a lever supporting one of said contacts, and a link connecting said lever with the bodily movable roll whereby upon abnormal approach of the latter toward the other roll the contacts will be separated by the action of said spring and the motor circuit broken.

8. In a machine for applying drop wires to loom warps, a plurality of magazines, an ejector for each magazine, means for operating said ejectors successively whereby normally to deliver a substantially continuous stream of drop wires, a power-driven feed roll, a detector roll, a pivoted support for the detector roll, a spring urging the detector roll toward the feed roll resiliently to grip all of the wires as delivered from the magazines and feed them toward the warp threads, an electric motor for driving the mechanism, normally engaging, relatively movable contacts in the motor circuit, a lever supporting one of said contacts, and means connecting the lever with the pivoted support of the detector roll whereby in response to interruption of the stream of wires the contacts will be separated and the motor circuit broken by abnormal approach of the detector roll to the feed roll.

Signed by me at Lawrence, Massachusetts, this 29th day of March, 1924.

SEBASTIANO MAGNANO.
